UNITED STATES PATENT OFFICE.

WILLIAM E. HUNT, OF OTTUMWA, IOWA, ASSIGNOR TO OTTUMWA BOX CAR LOADER CO.,
OF OTTUMWA, IOWA, A CORPORATION OF IOWA.

CAR-LOADER.

1,266,475.

Specification of Letters Patent. Patented May 14, 1918.

Application filed January 26, 1917. Serial No. 144,725.

To all whom it may concern:

Be it known that I, WILLIAM E. HUNT, a citizen of the United States, residing at Ottumwa, in the county of Wapello and 5 State of Iowa, have invented new and useful Improvements in Car-Loaders, of which the following is a specification.

This invention relates to improvements in car-loaders, proposing a construction of the 10 broad or general type disclosed in the U. S. Patent No. 632,202, granted to Henry Phillips and myself wherein a main frame laterally movable toward and from the car carries at one end an unloading hopper provided with material discharging means and 15 mounted for sliding movement in the direction of its length and also for pivotal movement about a vertical axis, the said hopper operating within the car and in relation to a 20 supply chute.

The principal objects of the invention are to provide a loader of the type stated which shall be particularly well adapted for use with coal of the smaller sizes or grades or 25 briquets but is also adapted for use with coal or coke of larger sizes and with various other materials; which shall perform its work expeditiously and with a minimum expenditure of power; and which shall effectively utilize the available capacity of the 30 car.

With the above objects in view the invention consists in certain features of structure, combination and relation which will appear 35 as the description proceeds.

An embodiment of the invention is illustrated in the accompanying drawings, wherein:

Figure 1 is a view in side elevation and 40 partial longitudinal section showing a car-loader in which the features of the invention are incorporated operating within a car.

Fig. 2 is a plan view thereof.

Fig. 3 is a detail sectional view on the line 45 3-3 of Fig. 1 showing the hopper and the material discharging means.

Fig. 4 is a plan view partly in section showing details of certain clutches by which different operations of the unloader are controlled.

Figs. 5, 6, 7 and 8 are detail sectional views on the lines 5-5, 6-6, 7-7 and 8-8, respectively, of Fig. 1.

Fig. 9 is a plan and Fig. 10 is a side elevation of the chain which in the present em-

bodiment constitutes the material discharging means.

Similar characters of reference designate corresponding parts throughout the several views.

The main frame, designated generally as 1, is movable laterally toward and from the car A and consists of parallel side bars 2 connected at appropriate intervals by sundry bars and plates, unnecessary to refer to 60 in detail, which are utilized to provide supports and bearings for various operating parts. Said main frame is mounted upon a supporting frame, designated generally as 3, which includes corner uprights 4 suitably 65 connected and braced. The uprights 4 are provided at their upper ends with rollers 5 which fit between the outer side flanges of the beams 2 to support the main frame from the supporting frame and to guide the main 70 frame in its movements laterally relatively to the car.

The machine may either be mounted on a stationary bed or it may be portable, as conditions may require. As shown, the supporting frame is mounted upon a wheeled 80 truck B.

In so far as the loader embodies as its principal parts the main frame 1, a loading hopper 6 supported at one end of the main 85 frame and a material-discharging means cooperating with the hopper and in so far as the hopper is an elongated, trough-like structure, open at its ends and of curved outline between its ends, and is mounted for sliding movement in the direction of its length and also for pivotal movement about a vertical axis, the loader is within the type illustrated in the Phillips and Hunt Patent 90 No. 632,202, previously mentioned.

The hopper 6 (Figs. 1 and 3) is supported by and slideable relatively to a cradle 7 which, in turn, is supported by the main frame and mounted for pivotal movement about a vertical axis. As supporting elements for said 100 hopper the cradle is provided with two pairs of rollers 8 which fit in channeled guides 9 provided at the sides of the hopper. The cradle 7 is provided with a discal base 10 which is journaled in a platform 11 secured at the outer end of the main frame, the said base and platform having their confronting circumferential faces formed to house and provide raceways for ball bearings 112 (Figs. 1 and 6).

According to the present invention, the material-discharging means operates continuously as the material is supplied to the hopper to drag the material from the point of supply toward the outer or remote end of the hopper from which it spouts or falls into the car. The said means, as shown and preferred, comprises an endless chain 13 (Figs. 1, 3, 9 and 10) provided at suitable intervals with arms 14 projecting laterally at each side thereof and movable along the bottom or base of the hopper.

The various instrumentalities of the machine derive their operations from a main shaft 15 which extends between and parallel to the side bars 2 of the main frame and is journaled in bearings supported by various cross bars extending between said side bars. A reversible electric motor 16 is preferably employed for operating the shaft 15 and is mounted at the inner end of the main frame. Said motor is connected to the shaft 15 by gearing 17 and its operation is regulated, as to speed and direction, by a controller 18 conveniently located on the main frame.

The chain 13, (Figs. 1, 3 and 6) is directly operated by the shaft 15 which drives a sprocket wheel 19 over which said chain 30 is trained. The sprocket wheel 19 has its vertical diameter coincident with the axial center of the cradle 7 by which it is carried and is connected universally to the shaft 15. For the support of the sprocket 19, the base 35 10 has a depending arm carrying a lateral journal post 20 upon which a hub extension 21 of the sprocket is rotatably mounted. The universal connection 22 between the sprocket 19 and the shaft 15 is similar to 40 that shown in Figs. 24 and 25 of the previously mentioned Phillips and Hunt Patent, No. 632,202. The cradle 7 includes a hollow standard 23 within which are mounted, in symmetrical co-planar relation to the sprocket 19, a pair of idler sprockets 24. The chain 13 is trained over the sprockets 24 and passes through diametrically opposite slots 25 in the standard 23. Other idler sprockets 26 over which the chain 13 45 is trained are mounted at the ends and below the base of the hopper 6 and one of the sprockets 26 is provided with a position adjusting device 27 whereby the tension of the chain 13 may be regulated.

50 The means operated by the shaft 15 for moving the main frame toward and from the car (Figs. 1 and 7) includes as its preferably principal element a chain or cable 28 whose ends are connected to bars or retaining devices 29 and 30 suitably located on the supporting frame 3 and as elements co-acting with said chain or cable, an operating wheel 31 located near the inner end of the main frame, a pair of sheaves 32 and 65 33 supported by the main frame and ar-

ranged in parallel relation at opposite sides of the wheel 31 and a single sheave 34 supported by the main frame near its outer end and located suitably distant from the sheaves 32 and 33. The laps of the chain 28 extend 70 in opposite directions or in crossed relation from the bars 29 and 30 and said chain, tracing it from the bar 29, is trained over the sheave 32, thence a half turn over the wheel 31, thence over the sheave 33 to the 75 sheave 34 and thence to the bar 30. It will be obvious that a rotation of the wheel 31 in either direction will cause the chain to be tensioned between the bar 29 and the sheave 32 or between the bar 30 and the 80 sheave 34 with a consequent movement, in one direction or the other as the case may be, of the main frame. Thus, when the chain 28, in consequence of the rotation of the wheel 31, exercises a pull on the sheave 85 32 in consequence of a reverse rotation of the wheel 31 the main frame will be projected, *i. e.*, moved toward the car. The wheel 31 is preferably loosely mounted on the shaft 15 and has attached thereto a 90 clutch element 35 for co-operation with a second clutch element 36 slidably keyed on said shaft and movable in either direction by an operating lever 37.

According to the present invention, the 95 turning movements of the cradle 7 and therewith of the hopper are positively controlled and effected by a mechanism which, when idle, holds said cradle in the position to which it has been moved and which may 100 be operated to turn said cradle through any extent necessary or convenient in connection with the operation of the loader. The said mechanism preferably comprises a chain 38 trained over an operating wheel 39 and connected at its ends to sheave segments 40 carried by the cradle 7 at opposite sides thereof. The chain wheel 39 is mounted on an upright shaft 41 driven from the shaft 15 by worm gearing 42 whose operation by the 110 shaft 15 is controlled by a suitable clutch. This clutch (Figs. 1 and 4) comprises an element 43 carried by the worm of the gearing 42, the said worm being loose on the shaft 15, and a co-operating element 44 slidably keyed on the shaft 15 and movable into or from engagement with the element 43 by a lever 45. It will be obvious that a rotation of the chain wheel 39 in either direction will produce a turning movement, in 120 the same direction, of the cradle 7.

According to the present invention the means for moving the hopper 6 in the direction of its length may be operated independently and during the operation of the 125 material discharging means. It preferably comprises (Figs. 1, 2, 3 and 8) a pinion 46 operated from the shaft 15 and a rack 47 carried by a flange of one of the guides 9 and with which said pinion, projecting into 130

said guide, is in mesh. The pinion 46 is mounted on a short shaft 48, having its bearing in a part of the cradle 7, and forms an element of a system of flexible shafting 5 which further comprises a shaft 49 geared to the shaft 15 and mounted for axial sliding movement and a rod 50 connecting the shafts 48 and 49 and articulated therewith by knuckle joints 51.

10 The bearings 52 (Fig. 4) in which the shaft 49 is slidable are carried by a pair of uprights 53 supported by the main frame. The gearing between the shafts 49 and 15 preferably comprises a sprocket 54 mounted 15 on the shaft 49 between the uprights 53 and through which said shaft is slidable, a sprocket wheel 55 loosely mounted on the shaft 15 and a chain 56 connecting the sprocket wheels 54 and 55. The shaft 49 20 preferably has a square or flat-sided cross-section in order that it may rotate, yet slide relatively to, the sprocket wheel 54.

For the purpose of controlling the rotation of the sprocket wheel 55 a clutch (Figs. 25 1, 2 and 4) is provided which comprises an element 57 carried by the sprocket wheel 55 and an element 58 slidably keyed on the shaft 15 and movable toward and from the element 57 by an operating lever 59. The 30 element 57 is formed externally to provide a brake drum for coöperation with a suitable brake band 60 connected by levers 61 to the lever 59 whereby the lever 59 when operated to disengage the clutch element applies the brake band 60 to the brake drum 35 and vice versa. In this way the hopper is held against retrograde movement when the clutch elements are disconnected yet may be freely moved in either direction, according 40 to the direction of rotation of the shaft 15, upon said clutch elements being engaged.

The operative steps in connection with the disposal of the hopper in the car and its withdrawal therefrom are the same as in the 45 previously mentioned Phillips and Hunt Patent No. 632,202 and, therefore, need not be repeated here. The operations of the mechanisms for moving the main frame and turning and sliding the hopper will be obvious from the drawings and preceding 50 description.

Within the car the hopper 6 is centered relatively to an overhanging supply chute C and is initially positioned with its discharge end in closest proximity to the cradle 7 and pointed toward one end of the car from which position it is moved slidably, in step by step fashion as need may require, toward the confronting end of the car; and 55 with each sliding movement its discharge end, in consequence of the curved outline of the hopper, is raised to a higher elevation, reaching its highest elevation when the hopper is fully projected relatively to the cradle 60 7, thereby piling the material to a depth 65

which increases regularly from the center to the end of the car. In this way the most effective utilization of the load receiving and storing capacity of the car is made. When the hopper has been fully projected 70 relatively to the cradle 7 and the loading of one end of the car has been completed, the rotation of the shaft 15 is reversed (by reversing the motor in the present embodiment)

whereby the chain 13 will move in the opposite direction to effect the discharge of material from the opposite end of the hopper. The loading of the opposite end of the car commences with the hopper in the fully projected position relative to the cradle 7 into 80 which it was moved during the previous operation, above described, and, as in the previous operation, the hopper is moved slidably, in step by step fashion as need may require toward the end of the car which its discharge end confronts until it reaches its fully projected position opposite to that reached in the first operation and which is its initial position, *i. e.*, the position it had at the commencement of loading. In short, the 90 hopper, fully projected, say to the left, is moved as far as possible toward the right to load the right end of the car from the center outward and is then moved toward the left and back to its initial position to load, 95 in like manner, the left end of the car, the chain 13 moving in the same direction as the hopper and, of course, having its movement reversed as the movement of the hopper is reversed. If necessary or desirable to facilitate loading, the hopper may be turned from time to time toward either side of the car as the loading progresses by operation of the mechanism provided for turning the cradle. 100

It is to be observed that in loading the 105 car at either end the operation is commenced at the discharge end of the hopper nearest to the floor and, as stated, as the loading progresses, the hopper is advanced through short distances. The hopper is only 110 moved forward, however, when the pile of material which it is forming has reached an elevation somewhat close to the hopper discharge end. A very important advantage is thereby secured in that the distance through 115 which the material falls from the discharge end of the hopper is at all times reduced to a minimum, and consequently, there will be no substantial breakage or reduction of the material of the load. 120

By proceeding in the manner described, the loading operation will be greatly expedited and a marked economy of power effected since the necessity of frequent reversals of the hopper is eliminated and since 125 the loading proceeds continuously with the discharge of material from the chute C.

It is to be understood that the present disclosure is of what is now considered a preferred embodiment, but that certain minor 130

changes within the legitimate scope of the appended claims may be resorted to without departing from the spirit or substance of the invention; and, therefore, that no specific 5 description herein contained is intended to impose any restriction upon the scope of the claims not inherent in their language or plain intent.

I claim as my invention—

- 10 1. In a car loader of the type set forth, the combination of an open ended hopper regularly curved from end to end thereof, a support for the hopper, the hopper being slidable in either direction of and substantially throughout its length relatively to said support and the latter co-acting with the hopper whereby to cause the path of its slideable movement to conform to the curved outline of the hopper, endless material engaging and moving means movable through the hopper, a continuously operating reversible shaft for effecting continuous movement of said means, the direction of movement of said means being dependent on the direction 15 of rotation of said shaft, and gearing connecting said shaft and said hopper whereby to effect the aforesaid slideable movement of the hopper, the direction of such movement being dependent on the direction of rotation 20 of said shaft and being the same as the direction of movement of said means, and a clutch for controlling the operation of said gearing whereby the hopper may be moved at will.
- 25 2. In a car loader of the type set forth, the combination of an open ended hopper regularly curved from end to end thereof, a support for the hopper, the hopper being slidable in either direction of and substantially throughout its length relatively to said support and the latter co-acting with the hopper whereby to cause the path of its slideable movement to conform to the curved outline of the hopper, material engaging and moving means including an endless 30 chain movable through the hopper, a continuously operating reversible shaft for directly driving said chain to effect a continuous operation of said means in a direction corresponding to the direction of rotation of said shaft, gearing operated by said shaft for effecting lengthwise movement of said hopper in the same direction in which said chain is moved and including a rack bar provided externally of the hopper and extending 35 between its ends and a pinion carried by said support and engaging said rack bar as a driving element therefor, and a clutch for controlling the operation of said gearing whereby the hopper may be moved at will.
- 40 4. In a car loader of the type set forth, the combination of a main frame mounted for slideable movement toward and from the car, an open-ended loading hopper slidably mounted at one end of said main frame, a support for said hopper, said support being mounted on said main frame to pivot about 45 a vertical axis and in its movement effecting pivotal movement of said hopper, material discharging means including an endless chain movable lengthwise of said hopper, means for moving said hopper slidably in a 50 direction of its length including a longitudinally extensible system of flexible shafting, said hopper supporting one of the end elements of said shafting, a support mounted on the main frame for the other end element of said shafting, a continuously operated reversible main shaft carried by said main frame and disposed longitudinally thereof for operating said material discharging means, gearing connecting an element of said flexible shafting and said main shaft to effect longitudinal movement of said hopper in the same direction in which said material discharging means is moved and a clutch for controlling the operation of 55 said gearing whereby the hopper may be moved at will.
- 60 5. In a car loader of the type set forth, in combination, a main frame, an open-ended hopper, a support for the hopper having an upright standard and a discal base rotatably mounted at an end of said main frame, the hopper being slidably fitted upon the upper end of the standard for movement in the direction of its length and having at one side thereof a rack which extends between its ends, a pinion carried by said support and engaging said rack, a continuously operable reversible main shaft disposed longitudinally of said main frame, an endless chain movable through the hopper and provided with regularly arranged material engaging arms, a sprocket arranged under said base for operating said chain and directly driven by said main shaft, longitudinally exten-

of sheaves carried by said main frame at opposite sides of said chain wheel, a single sheave carried by said main frame at a point remote from said pair of sheaves, a chain trained over said chain wheel and over said sheaves and having an end portion extending from said single sheave and an opposite end portion extending from one of said pair of sheaves, fixed devices independent of the main frame to which said end portions are respectively connected in crossed relation, a continuously driven reversible main shaft carried by and disposed lengthwise of said main frame and serving to operate said material discharging means, said chain wheel being loosely mounted on said shaft, and means for clutching said chain wheel to said shaft for operation thereby.

6. In a car loader of the type set forth, the combination of a main frame mounted for slideable movement toward and from the car, an open-ended loading hopper slidably mounted at one end of said main frame, a support for said hopper, said support being mounted on said main frame to pivot about 90 a vertical axis and in its movement effecting pivotal movement of said hopper, material discharging means including an endless chain movable lengthwise of said hopper, means for moving said hopper slidably in a 95 direction of its length including a longitudinally extensible system of flexible shafting, said hopper supporting one of the end elements of said shafting, a support mounted on the main frame for the other end element of said shafting, a continuously operated reversible main shaft carried by said main frame and disposed longitudinally thereof for operating said material discharging means, gearing connecting an element of said flexible shafting and said main shaft to effect longitudinal movement of said hopper in the same direction in which said material discharging means is moved and a clutch for controlling the operation of 100 said gearing whereby the hopper may be moved at will.

7. In a car loader of the type set forth, in combination, a main frame, an open-ended hopper, a support for the hopper having an upright standard and a discal base rotatably mounted at an end of said main frame, the hopper being slidably fitted upon the upper end of the standard for movement in the direction of its length and having at one side thereof a rack which extends between its ends, a pinion carried by said support and engaging said rack, a continuously operable reversible main shaft disposed longitudinally of said main frame, an endless chain movable through the hopper and provided with regularly arranged material engaging arms, a sprocket arranged under said base for operating said chain and directly driven by said main shaft, longitudinally exten-

sible flexible shafting for driving said pinion, gearing for driving said shafting from said main shaft to effect slidable movement of said hopper in the same direction as said chain, and a clutch for controlling the operation of said gearing whereby said hopper may be moved at will.

6. In a car loader of the type set forth, in combination, a main frame, an open-ended hopper, a support for the hopper having an upright standard and a discal base rotatably mounted at an end of said main frame, the hopper being slidably fitted upon the upper end of the standard for movement in the direction of its length and having at one side thereof a rack which extends between its ends, a pinion carried by said support and engaging said rack, a continuously operable reversible main shaft disposed longitudinally of said main frame, an endless chain movable through the hopper and provided with regularly arranged material en-

gaging arms, a sprocket arranged under said base for operating said chain and directly driven by said main shaft, longitudinally 25 extensible flexible shafting for driving said pinion, gearing for driving said shafting from said main shaft to effect slidable movement of said hopper in the same direction as said chain, a clutch for controlling the 30 operation of said gearing whereby said hopper may be moved at will, means connected to said standard for effecting turning movement of said support, gearing for operating said last-named means from said main shaft, 35 and a clutch controlling said last-named gearing.

In testimony whereof I have hereunto set my hand in presence of two subscribing witnesses.

WILLIAM E. HUNT.
